STOCK QUOTATION PROJECTING DEVICE

August D. Eitzen, New York, N. Y., assignor to
 News Projection Corporation, New York, N. Y.,
 a corporation of New York

Application April 10, 1929, Serial No. 354,034

7 Claims. (CL 88—24)

My present invention relates generally to stock quotation devices, and has particular reference to a stock quotation projecting machine.

It is customary practice at the present time to associate a stock ticker which is adapted to discharge marked tape in a substantially continuous manner with a projecting device through which the tape is made to pass and by means of which the markings on the tape are displayed upon a relatively large screen which commands a substantial observation area. After the tape leaves the projecting device it is guided toward a take-up or rewinding mechanism of suitable character.

It is frequently desirable to render the markings on the tape readable from different observation areas. For example, in many brokerage offices, a separate room is assigned to ladies, and a separate display screen in each room is therefore desirable. Similarly, it is often advantageous to have a main display screen in a public room and a second display screen in a private room.

Before pointing out the features of my present invention, I will premise that the projection of images onto two separated screens is a matter of considerable expense where a separate ticker and projecting device are provided for cooperation with each screen. On the other hand, if this expense were to be minimized by employing a single ticker and a pair of projecting devices through which the tape would successively pass, then the markings projected by the second projecting device would be objectionably late in time so far as the actual stock transactions indicated by such markings are concerned.

It is a general object of my present invention to provide a stock quotation projecting machine which may be efficiently and satisfactorily employed for the creation of images of tape markings on two independent and separated screens, without necessitating any of the expense involved in duplication of expensive parts.

Another object is to provide a machine of this character which will serve to create images on at least two screens with the same promptness as the same would have been produced upon a single screen in accordance with customary practice.

More particularly, it is an object of my invention to provide a projecting machine for use with a pair of differently directed display screens, the machine comprising a common ticker, a common projecting device, and means for creating the

desired images in a prompt and efficient manner on both screens.

Briefly, I accomplish this general object by creating a main beam of light which emanates from the projecting device after having passed through the tape, and by thereupon directing said beam partially toward one screen and partially toward the other screen. In the embodiment herein chosen for illustration and description, I split the main beam into two subordinate beams and provide means for directing these subordinate beams toward and onto the two display screens respectively.

It is a feature of my invention to provide a device which is extremely simple in structural nature and which involves a minimum of manufacturing expense so far as optical instruments are concerned. For example, in a preferred form, I resort to the employment of an optical device in the form of nothing more than a piece of glass having plane opposite surfaces. In addition to the foregoing, the elements of my apparatus require very little more than a series of suitable reflecting members which are obviously simple in structural nature, inexpensive, and extremely unlikely to cause any impairment in smooth operation.

For the attainment of the foregoing objects and such other objects as may hereinafter appear or be pointed out, I have illustrated two forms of my invention in the accompanying drawings, in which—

Figure 1 is an elevational view of a projecting device constructed in accordance with my present invention and showing diagrammatically the manner in which images are simultaneously produced on a pair of separated screens;

Figure 2 is a view taken from the right of Figure 1;

Figure 3 is a plan view of Figure 1 with one of the screens omitted; and

Figure 4 is a view similar to Figure 1, showing a modification.

Referring to the drawings, and particularly to Figure 2, I have diagrammatically illustrated a portion of a stock ticker 10 from which a marked tape 11 is adapted to be discharged. This tape has been shown entering and passing through a projecting device 12, after which it is led toward a suitable take-up or rewinding mechanism designated generally by the reference numeral 13.

The foregoing elements are designed to cooperate with a pair of screens 14 and 15. It is to be noted that these screens are substantially spaced from each other and command different

observation areas. Thus, I have shown the screen 15 positioned on a relatively high point and facing toward the right of Figure 1, whereas I have shown the screen 14 somewhat lower than the screen 15 and facing toward the front of Figure 1. The screen 15 in this way typifies the screen which would command an observation area in, for example, a public room, and the screen 14 may be said to represent a second screen arranged within a private office or the like.

In accordance with my invention, a suitable source of light (not shown) is arranged within the projecting device 12 and is adapted to project a beam 16 upwardly through the tape 11 as the latter passes through the device 12. Referring particularly to Figure 1, it will be seen that I have arranged an optical device in the form of a glass plate 17 arranged in the path of the main beam 16 and at substantially 45° to the latter, whereby the main beam 16 is split into two subordinate beams 18 and 19. The beam 18 passes directly through the glass plate 17, being slightly refracted but otherwise unchanged. The beam 19 is directed in a lateral direction by the reflecting action of the glass plate 17.

It is obvious that the splitting of the beam in this manner will leave only a portion of the light intensity in each of the subordinate beams, but at the same time each of the latter will carry the selfsame markings through which the main beam 16 has passed.

In Figure 1 I have shown a pair of objective lenses 20 and 21 arranged in the subordinate beams 18 and 19 respectively. The beam 18 is directed toward a reflecting surface 22, thence to a second reflecting surface 23, and projected from the latter onto the rear of the screen 15, which, in this instance, would obviously be of a translucent character so that the markings 24 would appear on the front face of the screen as shown in Figure 2.

The beam 19 is directed toward and onto a reflector 25 and thence forwardly onto the rear of the screen 14, this screen also being of a translucent character to render the markings 26 visible on the front face thereof. It is to be noted that the markings 24 and 26 are identical and are produced on their respective screens simultaneously.

In Figure 4 I have illustrated the possibility of arranging a glass plate 27 above a single objective lens 20' for the purpose of fulfilling the same general object in a slightly different manner. It is to be noted that the objective 20' is positioned in the main beam 16 prior to its separation into the two subordinate beams. A suitable reflector 28' is arranged in the path of the subordinate beam 28 in a manner similar to the arrangement of the reflector 25 in the path of the corresponding beam 19 of Figure 1.

It is to be noted that the reflecting members are so arranged as to create direct and uninverted images on both screens. Since one reflection would cause an inversion whereas two reflections, or any even number of reflections, would cause a rectification, it is obvious that the two reflectors 22 and 23 accomplish the desired object with respect to the screen 15, whereas the reflector 25 in conjunction with the reflection of the glass plate 17, produces the desired effect with respect to the screen 14.

It will thus be seen that I have provided a device which is extremely efficient yet exceptionally simple in structural nature and inexpensive from a manufacturing standpoint. A single tick-

er and a single projecting device are employed. The markings displayed on each of the screens are equally prompt with respect to the passage of the tape through the projecting device 12. And the provision of reflectors such as the members 22, 23, and 25, adjacent to respective screens, may be expeditiously provided for without resulting in any cumbersome or objectionable space-occupying structure.

It will be obvious that the splitting of the beam 16 may be accomplished within the projecting device itself after passage through the tape, the forms illustrated serving merely to show the optical features of my invention. For example, if the glass plate 17 and one or more desired objective lenses were arranged within the projecting device 12, then the two subordinate beams might be caused to emanate from two different openings in the projecting device itself. Similarly, a suitable rearrangement of reflecting surfaces will render it possible to project markings simultaneously upon screens positioned in different divergent and spaced manners from those illustratively shown.

In general, it will be obvious that changes in the details herein described and illustrated for the purpose of explaining the nature of my invention may be made by those skilled in the art without departing from the spirit and scope of the invention as expressed in the appended claims. It is therefore intended that these details be interpreted as illustrative and not in a limiting sense.

Having thus described my invention and illustrated its use what I claim as new and desire to secure by Letters Patent is—

1. In a stock quotation projecting machine having a ticker adapted to mark and discharge tape with reading matter readable longitudinally of the tape, the combination with a pair of independent and separated elongated narrow daylight display screens, of a projecting device removed from said screens through which device the marked tape passes, said device including a source of light, and elongated light aperture along which the tape passes to receive the light rays from said source of light and form images of the markings on said tape, means for splitting said light rays into two subordinate beams after passing through said tape, and sets of reflectors so arranged as to direct said last-named beams toward and onto said screens respectively so as to produce erect and uninverted images on each screen movable and readable longitudinally of such screen.

2. In a stock quotation projecting machine having a ticker adapted to mark and discharge tape with reading matter readable longitudinally of the tape, the combination with a pair of screens facing in divergent directions, of a common projecting device through which the marked tape passes, said device including a common source of light, an elongated narrow light aperture along which the tape passes to receive light rays from said light source and form images of the markings on said tape, means for splitting said light rays into two subordinate beams after passing through said tape, said means comprising a glass plate arranged in the path of said beam at substantially 45° to the axis of the latter, and reflecting means for directing said subordinate beams toward and onto said screens respectively to produce erect and uninverted lon-

gitudinally movable and readable images of said markings on each of said screens simultaneously.

3. In a stock quotation projecting machine having a ticker adapted to mark and discharge tape with reading matter readable longitudinally of the tape, the combination with a pair of independent and separated elongated narrow daylight display screens, of a projecting device removed from said screens through which device the marked tape passes, said device including a source of light, an elongated light aperture along which the tape passes to receive the light rays from said source of light and form images of the marking on said tape, means for splitting said light rays into two subordinate beams after leaving said tape, said means comprising a glass plate arranged in the path of said light rays at an angle to the axis of said light rays, and sets of reflectors so arranged as to direct said last named beams toward and onto said screens respectively so as to produce erect and uninverted images on each screen movable and readable longitudinally of such screen.

4. In a stock quotation projecting machine having a ticker adapted to mark and discharge tape with reading matter readable longitudinally of the tape, the combination with a pair of independent elongated narrow daylight display screens facing into different inspection areas, of a projecting device removed from said screens through which device the marked tape passes, said device including a source of light, an elongated light aperture along which the tape passes to receive the light rays from said source of light and form images of the marking on said tape, means for splitting said light rays into two subordinate beams after leaving said tape, and sets of reflectors so arranged as to direct said last named beams toward and onto said screens respectively so as to produce erect and uninverted images on each screen movable and readable longitudinally of such screen.

5. In a projection system, the combination with a projection field along which a tape having characters reading lengthwise thereof is movable

in a horizontal direction, of a screen disposed in a vertical plane extending crosswise with respect to the course taken by the tape while moving through said projection field, and means comprising a light reflecting system for producing on said screen character images which travel horizontally from end to end thereof in a plane that is substantially perpendicular to the plane of the tape section in said projection field.

6. In a projection system, the combination with a projection field along which a tape having characters reading lengthwise thereof is movable in a horizontal direction, of a screen disposed in a vertical plane extending crosswise with respect to the course taken by the tape while moving through said projection field, and means comprising a light reflecting system for transferring onto said screen characters appearing on the horizontally traveling tape, in the form of character images which travel horizontally from end to end of the vertically disposed screen.

7. In a stock quotation projecting machine having a ticker adapted to mark and discharge tape with reading matter readable longitudinally of the tape, the combination with a pair of elongated narrow daylight display screens facing into different inspection areas, of a projecting device removed from said screens through which device the marked tape passes, said device including a source of light, an elongated light aperture along which the tape passes to receive the light rays from said source of light and form images of the marking on said tape, a single objective lens unit for receiving the image impressed light rays after passing through the tape, means for receiving the image impressed light rays from said objective lens unit and splitting them into two separate light beams, and reflecting means for receiving and directing the last named separate light beams toward and onto said screens respectively so as to produce erect uninverted images on each screen movable and readable longitudinally of such screen.
